UNITED STATES PATENT OFFICE.

WILLIAM H. SAUVAGE, OF FLUSHING, NEW YORK, ASSIGNOR TO GOULD COUPLER COMPANY, A CORPORATION OF NEW YORK.

SLACK-ADJUSTER.

1,227,942.

Specification of Letters Patent. Patented May 29, 1917.

Application filed January 25, 1916. Serial No. 74,178.

To all whom it may concern:

Be it known that I, WILLIAM H. SAUVAGE, citizen of the United States, and resident of Flushing, Long Island, and State of New York, have invented certain new and useful 5 Improvements in Slack-Adjusters, of which the following is a specification.

This invention relates to slack adjusters for the brake rigging of railway cars and 10 in its more intense aspect to improvements in the foundation brake rigging as will be hereinafter more fully described.

One of the objects of the present invention is to provide a simple and practical 15 arrangement of the foundation brake rigging equipped with automatic slack adjusters associated either with the truck brake rigging or the power cylinder adapted to insure uniform piston travel. A further 20 object is to provide mechanism of the above general character in which the relative positioning and range of movement of the elements constituting the brake rigging will be substantially uniform at all times. A 25 further object is to provide a mechanism of the above mentioned character having few parts which will be inexpensive to manufacture and install.

Other objects will be in part obvious from 30 the annexed drawings and in part indicated in connection therewith by the following analysis of this invention.

This invention accordingly consists in the features of construction, combination 35 of parts and in the unique relations of the members and in the relative proportioning and disposition thereof, all as more completely outlined herein.

To enable others skilled in the art so fully 40 to comprehend the underlying features thereof that they may embody the same by the numerous modifications in structure and relation contemplated by this invention, drawings depicting a preferred form have 45 been annexed as a part of this disclosure, and in such drawings, like characters of reference denote corresponding parts throughout all the views, in which—

Figure 1 is a diagrammatic view showing 50 such parts of a brake rigging as are necessary to understand the present invention;

Figs. 2 and 3 are detail views partly in section of adjustable hangers.

Referring now to the drawings in detail and more particularly to Fig. 1, 5 denotes a power cylinder preferably secured to the under side of the car body or framework in the usual manner. This cylinder is provided with a piston 6 pivotally connected at the point 7 with a primary live lever 8 of the brake rigging. This live lever is connected at one end 10 with a pull rod 11 leading to hand brake mechanism 12 at the end of the car, while its opposite end 13 is pivotally connected with a pull rod 14 connected at the point 15 with the upper end of truck live lever 16.

On the same truck is also mounted dead lever 18 from adjustable stationary hanger 20 having its lower end 21 connected with the corresponding end of the live lever by means of a telescopic push rod 22—23. This telescopic push rod constitutes an automatic slack adjuster which may be of any desired type such for example as described in pending application Serial Number 74,176, filed January 25, 1916, of mine, the main purpose being to take up, register and permanently hold any excess travel that may occur due to wear of the parts and 80 brake shoes. These live levers are associated with brake beams 24 in the present form carrying brake shoes coating with the peripheries of the wheels as is well known to those familiar with the art.

The truck at the opposite end is provided with mechanism of the same general character, that is a push rod 14 is connected at the point 25 with one end of the lever 26, the opposite end of which is pivotally secured to a stationary point 27. Intermediate the primary levers 26 and 8 is a tension member 28 for the purpose of transmitting power from one to the other. These levers are all so positioned, proportioned and arranged as to properly transmit the power from the power cylinder in a substantially equal amount to the various brake shoes.

In order to insure uniform piston travel at all times and the maintaining of substantially uniform relation and range of movement of the several levers with respect to the power cylinder, there is secured to the under side of the car brackets 30 and 31 in which the levers 8 and 26 respectively are adapted to rest. Both of these brackets are

U-shaped and provided with adjustable stops 32 which may be clamped in any desired position upon the brackets, as shown more clearly in Figs. 2 and 3.

5 Now as the brakes are applied, the piston 6 moves outwardly with respect to the stationary cylinder 5 and carries the connected end of the lever 8 toward the right. A reactive pull will take place upon the tension member 28 to move the lever 26 also to the right a proportional amount. These movements react through the pull rods 14 and associated live and dead truck levers to apply the brakes in a substantially uniform manner to the peripheries of the several wheels.

20 As the wear takes place upon the brake shoes, the relative position of the truck levers will change somewhat and this variation would otherwise be transmitted through the intervening connections to the brake cylinder were it not for the application of the supporting brackets and adjustable stops which maintain these parts in proper relative position. Therefore by placing the brackets 30 and 31 in substantially the manner shown, the levers 8 and 26 always have a uniform range of movement and the rest of the mechanism will automatically accommodate itself to such range.

25 It is thus seen that the present invention provides a simple, practical, reliable and efficient mechanism primarily adapted to maintain uniform position of the various parts of the foundation brake rigging, and is believed to accomplish, among others, all of the objects and advantages herein set forth.

30 Without further analysis, the foregoing 40 will so fully reveal the gist of this invention that others can by applying current knowledge readily adapt it for various applications without omitting certain features that, from the standpoint of the prior art, 45 fairly constitute essential characteristics of the generic or specific aspects of this invention, and therefore such adaptations should and are intended to be comprehended within the meaning and range of equivalency of 50 the following claims.

I claim:

1. In apparatus of the character described, in combination, a power cylinder, a lever associated therewith having operative connections with the truck brake rigging, means adapted to support said lever from the under side of the car body to insure uniform range of movement and a variable stop associated with said means.

60 2. In apparatus of the character described, in combination, a power cylinder, levers associated therewith having operative connections with the truck brake riggings, brackets secured to the under side of the car body adapted to support said levers and

limit their range of movement in both directions and clamps on said brackets movable to adjusted position to vary the range of movement of said levers.

3. In apparatus of the character described, 70 in combination, a power cylinder, live and dead levers associated therewith having operative connections with the truck brake riggings, lever supports secured in relatively fixed position adapted to support said levers 75 and limit their range of movement, and variable means on said supports whereby the range of movement of the levers may be further adjusted and limited.

4. In apparatus of the character described, 80 in combination, a power cylinder, levers associated therewith having operative connections with the truck brake riggings, and brackets secured in relatively fixed position adapted to support said levers and limit 85 their range of movement, and means whereby the range of movement of the levers may be further adjusted and limited, said means comprising a clamp secured to said bracket and adapted to engage the associated lever 90 at one of its limits of movement.

5. In apparatus of the character described, 95 in combination, a power cylinder, live and dead levers associated therewith, truck brake riggings operatively connected with the primary live and dead levers, automatic slack adjusters associated with the truck brake rigging, and means adapted to limit the movement of the levers and maintain them in a predetermined relation with respect to 100 the power cylinder.

6. In apparatus of the character described, 105 in combination, a power cylinder, primary levers associated therewith, truck brake riggings operatively connected with the primary levers, automatic slack adjusters associated with the truck brake rigging, means adapted to limit the movement of the primary levers and maintain them in predetermined relation with respect to said power 110 cylinder, said means comprising supports secured to the under side of the car engaging said levers intermediate their ends and stops adjustably mounted on said supports.

7. In apparatus of the character described, 115 in combination, a power cylinder, primary levers associated therewith, truck brake riggings operatively connected with the primary levers, automatic slack adjusters associated with the truck brake rigging, and means 120 adapted to limit the movement of the primary levers, said means comprising supports engaging said levers intermediate their ends and friction clamping members adapted to grip said supports and coact with the associated levers at one end of their range of movement.

8. In an apparatus of the character described, 125 in combination, a power cylinder, primary levers associated therewith, brake 130

rigging having automatic slack adjusters associated therewith and connected with said primary levers, and supporting members carrying adjustable stops for said primary levers mounted on the car body adapted to adjustably limit the movement of said levers within their maximum range of travel

whereby said automatic slack adjusters are brought into operation and cause a more uniform action and wear of the brakes. 10

Signed at New York in the county of New York and State of New York this 16th day of December A. D. 1915.

WILLIAM H. SAUVAGE.
